UNITED STATES PATENT OFFICE.

GEORGE H. GIBSON, OF ST. LOUIS, MISSOURI, ASSIGNOR TO COMMONWEALTH STEEL COMPANY, OF ST. LOUIS, MISSOURI, A CORPORATION OF NEW JERSEY.

LOCOMOTIVE TRUCK.

Application filed January 10, 1925. Serial No. 1,621.

To all whom it may concern:

Be it known that I, GEORGE H. GIBSON, a citizen of the United States, residing at St. Louis, Missouri, have invented a certain new 5 and useful Improvement in Locomotive Trucks, of which the following is a specification, such as will enable others skilled in the art to which it appertains to make and use the same.

10 My invention relates to railroad rolling stock and particularly to the construction of trucks which include rocker bearings. Where such bearings are provided, it will be understood that the parts carried by the 15 rockers have movement in the plane of the rocking motion of the rockers. In addition to this movement, there is a bodily movement of the parts carried by the rockers in a direction transversely of the plane 20 of rocking motion. This latter movement tends to disalign the rockers and the rocker seats and the elements mounted on the rockers, and the object of my invention is to provide means for maintaining proper 25 alignment of these parts, for limiting bodily movement of the elements transversely of the rocking motion and for receiving the wear due to such motion. Preferably this means is renewable so that after consider- 30 able wear has taken place, the original relation may be maintained by replacing the worn means.

In the accompanying drawings which illustrate a selected embodiment of my invention—

Figure 1 is a top plan view of a locomotive two wheel truck equipped with rocker bearings for its bolster element.

Figure 2 is in part an end view of the 40 truck and in part a vertical transverse section on the center line of the truck.

Figure 3 is a vertical longitudinal section taken on line 3—3 of Figure 1.

The truck comprises the usual wheels 1, 45 axle 2, boxes 3, and springs 4. Mounted on the springs is a frame 5 here shown as a one-piece casting. Frame 5 includes brackets 6 which carry rocker seats 7. These rocker seats mount rockers 8 which have a 50 rocking motion on their seats transversely of the truck. Preferably, rockers 8 are arranged in pairs, one pair at the front of the truck and one pair at the rear. The rockers of each pair are aligned transversely of 55 the truck and cooperate in supporting a

rocker bearing 9 which is vertically aligned with its respective rockers 8.

A bolster 10 rests upon rocker bearings 9 and the bolster and rocker bearing are secured to each other by countersunk rivets 60 11. It will be noted that rocker bearing 9 is in vertical alignment with rockers 8. It will also be noted that bolster 10, rocker bearings 9, and rockers 8 are positioned between the side walls 12 of the truck frame. As the load on the bolster shifts longitudinally 65 of the truck, there will be movement of the bolster and rocker and rocker bearings to and from the opposite walls 12 and this movement is limited by chafing plates 13 secured 70 to the frame walls by means of countersunk rivets and preferably formed of hard steel to better withstand the friction of the rockers and rocker bearings. In the absence of 75 this plate, either the rocker or the rocker bearing might shift so that one of the edges of one of these elements would be intermediate the edges of the other of the elements, and if the devices should rock while in this disaligned position, the bearing area 80 would be reduced. Repeated rockings would result in a shoulder or shoulders being produced in the bearing surfaces by the edges of the opposing elements.

I have previously referred to the fact that 85 plates 13 are renewable, but, as a matter of fact, when these plates are made of hardened steel, any wear which takes place will be on the relatively softer rocker and rocker bearings and if the play becomes too great, the 90 rocker and rocker bearing may be replaced. In no event will there be wear upon the relatively large and expensive frame, nor will it be necessary to operate with a greater 95 clearance than is desired because of the difficulty or expense of maintaining the desired minimum clearance between the rocker and bearing and the surfaces which limit the movement of these parts longitudinally of 100 the truck.

While each of plates 13 may extend past both rockers 8 on its side of the truck, it is practical to provide individual plates for each rocker and at the upper portion of Figure 1, such an arrangement is indicated. 105 Obviously, this and other modifications of the details of my invention may be made without departing from the spirit of my invention, as expressed in the following 110 claims, and I contemplate the exclusive use

of such variations as may be covered by my claims.

I claim:

1. In a truck, a frame, a rocker having movement transversely of the plane of its rocking motion, a bearing mounted on said rocker, and a chafing plate on said frame adjacent said rocker and bearing for limiting said movement of said rocker relative to said bearing.
2. In a truck, a frame, a rocker carried thereby, a rocker bearing supported by said rocker, a bolster carried by said bearing, and a chafing plate on said frame adjacent said rocker and bearing for engaging the same when said bolster moves longitudinally of the truck.
3. In a truck, a frame including a rocker seat, a rocker thereon rocking transversely of the truck and having bodily movement longitudinally of the truck, and a hardened steel plate applied to said frame so as to engage said rocker and limit its bodily movement.
4. In a truck, a frame including a rocker seat, a rocker thereon rocking transversely of the truck and having bodily movement

longitudinally of the truck, and a renewable chafing plate applied to said frame so as to engage said rocker and limit its bodily movement.

5. In a truck, a frame including parallel vertical walls extending transversely of the truck, rocker seats, rockers on said seats rocking transversely of the truck, a bolster carried by said rockers, said rockers and bolster being located between said walls and having movement longitudinally of the truck to and from said walls, and renewable chafing plates on said walls to maintain a substantial alignment of said rockers and bolster.

6. In a truck, a frame, a rocker seat thereon, rockers on said seat normally aligned with each other in the plane of their rocking motion, a rocker bearing resting on said rockers, a bolster carried by said bearing, and chafing plates on said frame for maintaining said rockers in substantial alignment with each other and with said bearing.

In testimony whereof I hereunto affix my signature this 5 day of January, 1925.

GEO. H. GIBSON.
